US0D1101750S

(12) United States Design Patent (10) Patent No.: US D1,101,750 S
(45) Date of Patent: * Nov. 11, 2025

(54) SMART WATCH

(71) Applicant: Samsung Electronics Co., Ltd.,
Suwon-si (KR)

(72) Inventors: Sangsung Woo, Suwon-si (KR); Insik Chung, Suwon-si (KR)

(73) Assignee: SAMSUNG ELECTRONICS CO., LTD., Suwon-si (KR)

() Term: 15 Years

(21) Appl. No.: 29/954,145

(22) Filed: Jul. 25, 2024

(30) Foreign Application Priority Data

Jan. 26, 2024 (KR) 30-2024-0003730

(57) CLAIM

The ornamental design for a smart watch, as shown and described.

DESCRIPTION

FIG. 1 is a front perspective view of a smart watch showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The dashed broken lines in the figures depict portions of the smart watch that form no part of the claimed design.

1 Claim, 8 Drawing Sheets
